UNITED STATES PATENT OFFICE.

WILLIAM R. REPPELL, OF ST. LOUIS, MISSOURI, ASSIGNOR OF ONE-HAIF
TO LOUIS H. REPPELL, OF KANSAS CITY, MISSOURI.

DANCING TOY.

SPECIFICATION forming part of Letters Patent No. 692,907, dated February 11, 1902.

Application filed March 1, 1901. Serial No. 49,383. (No model.)

To all whom it may concern:

Be it known that I, WILLIAM R. REPPELL, a citizen of the United States, residing at St. Louis, in the State of Missouri, have invented 5 a new and useful Dancing Toy, of which the following is a specification.

My invention relates to amusement devices, and more particularly to dancing toys; and my object is to produce a device of this character which can be made to clog-dance in harmony with any of the simple and popular airs of the day and in a most natural and life-like manner.

With this object in view the invention consists in certain novel and peculiar features of construction and combinations of parts, as hereinafter described and claimed, and in order that it may be fully understood reference is to be had to the accompanying drawings, 20 in which—

Figure 1 represents a perspective view of a dancing toy embodying my invention. Fig. 2 represents a side view, partly in section, of a portion of the toy. Fig. 3 is a perspective 25 view showing a slightly-modified form of construction.

In the said drawings, where like reference-numerals designate corresponding parts, 1 designates a figure, preferably the representation 30 of a human being and constructed of wood, sheet metal, or any other suitable material, the figure comprising, preferably, a series of parts pivoted together, as at 2, so that each of said parts shall have more or less independent movement, all being arranged to operate preferably in the same vertical plane. The hat or head portion of the toy is pivotally suspended, as at 3, in the same or a parallel plane with pivots 2 from 35 the front end of a support 4, the same preferably consisting of a rigid rod bent to approximately right-angle shape. The lower end of said rod or support extends through an opening 5 in the platform, said platform consisting of a dancing-floor 6 and a rear portion 7, the latter adapted to be held rigidly, as by laying it flatly on a surface—such as a chair, for instance—and throwing one's leg over it in order that the dancing-floor may be caused 50 to vibrate in a manner hereinafter explained

in a vertical direction. The lower end of the rod or support just below opening 5 is securely wedged or fastened in a preferably rigid arm 8, underlying and secured to the rear portion 7 of the platform.

In Fig. 3 it will be noticed that I show a pair of dancing figures, which may be connected to the cross-rod 9, attached to the front end of rod or support 4 in the manner described, or which may be suspended from said cross-rod by means of retractile springs 10, which of course will admit of considerable lateral movement of the figures as well as forward-and-backward movement, it being understood, of course, that the pivot 3 may also be sufficiently loose to permit the figure suspended therefrom to have a limited amount of lateral movement also.

In operation the rear portion of the platform is secured as before explained or in any other suitable or preferred manner, and then the operator by tapping upon the platform at a suitable point, preferably adjacent to the support 4, causes said platform to vibrate with more or less regularity and rapidity, which vibrations by pushing upwardly against the feet of Fig. 1, which are arranged to barely touch the platform when inoperative, cause said figure to dance in a very life-like manner, the feet coming in contact with the dancing-floor and producing a sound exactly like that of a clog-dancer, and it has been found that with more or less practice one can compel the figure to keep time with an instrument playing a simple piece of music or with the voice. The vibrations of the platform may be induced also by picking with the thumb upon the front end of the dancing-floor in imitation of the manner in which a banjo or guitar is played.

In the present application the essential feature of difference over what has hitherto been done in devices of this character consists in the fact that my support beneath the body, arm, and figure support up to the pivotal point are all rigid while the dancing-floor alone vibrates, while in previous constructions either the figure alone vibrated or else both the figure and the floor vibrated. Moreover, the support for the figure is held in

the present case by a rigid arm, which in turn is fastened to the flexible floor at a point where the latter has practically no movement, because it is held beneath the body of the operator or is firmly secured to some other support.

From the above description it will be apparent that I have produced a dancing toy which embodies the features of advantage 10 enumerated as desirable in the statement of invention and which also possesses the very desirable elements of simplicity and cheapness, and while I have illustrated and described the preferred embodiment of the invention it is to be understood that it is susceptible of modifications in various particulars without departing from the principle of construction herein shown.

Having thus described the invention, what

I claim as new, and desire to secure by Letters 20 Patent, is—

In a dancing toy, the combination with a flexible floor adapted to be held rigidly at its inner end under the body of the operator; of an unyielding arm secured rigidly at its inner end to the bottom of the floor near the support of the latter, a rigid support rising from the forward end of said arm and passing loosely through a hole in the floor, and a figure pivotally carried by said support with 25 its feet resting upon said floor.

In testimony whereof I affix my signature in the presence of two witnesses.

WILLIAM R. REPPELL.
